BRUSHMAKING MACHINE

Alfred L. Le Febvre, Windsor, Conn., assignor to
 The Fuller Brush Company, Hartford, Conn.,
 a corporation of Connecticut

Application May 2, 1946, Serial No. 666,735

24 Claims. (Cl. 300—2)

1

The invention relates to a machine for making brushes of the type wherein the brush bristles or fibers are held between two wires which are twisted to grip and retain them. A machine embodying the present invention is in some respects similar to that shown in Patent No. 2,358,443, issued September 19, 1944, in the names of Henry Cave et al.

The machine shown in the said patent is a fully automatic machine which is entirely suitable for brushes of certain types. For brushes of other types, particularly when high grade, expensive fibers are used, a semi-automatic machine is preferable so that the operator may have opportunity to visually inspect the fibers of each brush prior to the twisting of the wires to make sure that the fibers are properly distributed, and to manually change the distribution of the bristles when this may appear to be necessary. After inspection of the fibers by the operator and after any necessary adjustment of the distribution thereof, the twisting mechanism of the machine can be started in operation by the operator to effect the twisting of the wires to hold and grip the fibers.

One of the objects of the invention is to provide a machine of the general character referred to having a magazine for brush fibers and having a carrier which is adapted to be positioned adjacent the magazine to receive fibers therefrom and which then moves in a generally horizontal direction to a twisting position within convenient reach of the operator so that the necessary inspection and distribution of the fibers can be taken care of prior to twisting.

A further object of the invention is to provide a machine having a carrier which reciprocates horizontally between a fiber receiving position adjacent the magazine and a forward twisting position, the said twisting position being as before stated, within convenient reach of the operator.

A further object of the invention is to provide, in association with the horizontally movable carrier, an automatically operated wire feeding means which serves to feed one wire to the carrier prior to the distribution of brush fibers thereon, and which serves to feed a second wire to the carrier after the distribution of brush fibers thereon.

A still further object of the invention is to provide a machine of the general character already set forth wherein the carrier not only moves horizontally as stated, but also moves vertically, thus enabling a more satisfactory spaced rela-

2

tionship between the fiber magazine and the twisting position.

A still further object of the invention is to provide a machine of the general character described wherein the carrier, after reaching the twisting position and after the wires thereon have been gripped by the twisting mechanism, can be moved vertically downward to provide ample space for the twisting operation without any interference with such operation by the carrier.

A still further object of the invention is to provide a machine having the general characteristics already set forth wherein the twisting mechanism is bodily movable horizontally with the carrier, but wherein the carrier may be movable vertically independently of the twisting mechanism.

Various other objects of the invention will be apparent from the drawings and from the following specification and claims.

In the drawings I have shown in detail a preferred embodiment of the invention, but it will be understood that various changes may be made from the construction shown, and that the drawings are not to be construed as defining or limiting the scope of the invention, the claims forming a part of this specification being relied upon for that purpose.

Of the drawings, Figs. 1 to 6, inclusive, are schematic views of a portion of a machine embodying the invention, these views showing the essential functioning of those parts of the machine to which the invention more particularly relates.

Fig. 7 is a front view of the machine, this view showing a brush in its twisted condition.

Fig. 8 is a transverse vertical sectional view taken along the line 8—8 of Fig. 7.

Figs. 9 and 10 are detail views illustrating the manner of operation of the wire feeding means.

Fig. 11 is a transverse vertical sectional view taken along the line 11—11 of Fig. 7.

Fig. 12 is an enlarged fragmentary detail view showing a part of the mechanism for operating the magazine for brush fibers, this view being taken along the line 12—12 of Fig. 20.

Fig. 13 is a view of the same parts shown in Fig. 12, but taken along the line 13—13 of Fig. 20.

Fig. 14 is an enlarged plan view of the carrier for the brush fibers and the wires, together with parts immediately associated therewith including portions of the vise and chuck of the twisting mechanism.

Fig. 19 is an enlarged horizontal sectional view taken along the line 19—19 of Fig. 8 and also along the line 19—19 of Fig. 20, this view showing parts of the mechanism for operating the magazine for brush fibers.

Fig. 20 is another enlarged view of the mechanism for operating the magazine for brush fibers, this view being partly in section along the line 20—20 of Fig. 11.

General description

Referring particularly to Figs. 1 to 6 of the drawings, it will be seen that the machine is provided with a carrier 10 which is horizontally movable with respect to a main bed or base 12. This carrier has a generally horizontal portion and is adapted to receive and carry two horizontal wires with a horizontal layer of brush fibers between the wires and extending transversely thereof. Suitably mounted in fixed relation to the base 12 is a magazine for brush fibers generally indicated at 14, and there is preferably also provided a wire feeding means generally indicated at 16. The carrier 10 can occupy a forward twisting position as shown in Fig. 1 in which position it is parallel with the magazine and in which position the wires can be twisted by a suitable twisting mechanism, a part of which is shown at 18, and it can also occupy a rearward position immediately adjacent the magazine 14, as shown in Fig. 3, in which position it can receive a layer of fibers from the magazine 14. Preferably, provision is made for reciprocable movements of the carrier between these two positions, the carrier being moved translationally and in parallelism, each position thereof during movement being parallel with each other position. The carrier is shown as mounted on a slide 20 horizontally movable along a guideway 21 formed on the base 12. When a wire feeding means such as 16 is provided, this means serves to deposit one wire A on the carrier in the position shown in Fig. 2 as the carrier moves from its twisting position shown in Fig. 1 to its fiber receiving position shown in Fig. 3.

With the carrier in the position shown in Fig. 3 a layer B of brush fibers is distributed on the carrier in a manner to be described in detail, and then the carrier is returned to the twisting position as shown in Fig. 5. In moving from the position shown in Fig. 3 to the position shown in Fig. 5 the carrier passes through the intermediate position shown in Fig. 4 and in this position the wire feeding means 16 serves to deposit a second wire C on the carrier, the carrier then carrying the two wires A and C with a layer B of brush fibers between them. When the position shown in Fig. 5 is reached the layer of fibers on the carrier between the two wires can be inspected by the operator and any necessary redistribution of the fibers can be made. It is frequently desirable to remove a few fibers from each end of the layer B to insure more satisfactory twisting. After the fibers have been inspected and redistributed, the wires A and C are then gripped in the usual manner by the aforesaid twisting means located at the twisting position. The twisting means serves to twist the two wires in

accordance with standard practice to form a twisted brush. In order that twisting may be effected by the twisting means without interference by the carrier, the carrier is moved downward prior to twisting to the position shown in Fig. 6.

Preferably but not necessarily, the fiber magazine 14 is in a relatively elevated position and the carrier in moving from the position shown in Fig. 1 to the position shown in Fig. 3 moves not only horizontally, but also vertically upward. In returning from the position shown in Fig. 3 to the position shown in Fig. 5, the carrier moves vertically downward.

A portion 18 of the twisting mechanism is shown in the twisting position by dotted lines in Figs. 2, 3 and 4, but the said twisting means is not necessarily permanently located in the said position. While the invention is not necessarily so limited, the slide 20 which supports the carrier 10 may also support the twisting mechanism. Thus the twisting mechanism is movable bodily with the carrier, the carrier and the twisting mechanism remaining in fixed relationship to each other, except that the carrier is or may be movable vertically as already stated.

The details of the carrier, of the fiber magazine, of the wire feeding means, and of various associated parts, together with the manner of operation, will now be described.

Carrier and operating mechanism therefor

In describing the carrier and the operating mechanism therefor reference will be had more particularly to Figs. 7, 8, 11, 14 and 18.

For supporting the carrier 10 there is provided a bracket 22 which is rigidly mounted on the slide 20. A slide 24 is provided which is vertically movable in suitable guideways in the bracket 22, being held in place by gibbs 26, 26. The slide 24 has an integral rearward extension 28 and the carrier 10 has a cylindrical bottom portion which is directly supported in an opening in the upper end portion of the extension 28. The carrier has an integral lug 29 thereon which engages a notch in the slide 24 to prevent the carrier from turning. As shown more clearly in Fig. 11, the slide 24 and the extension 28 thereof extend downward through an aperture in the main slide 20.

As shown in Figs. 7, 14 and 18, the carrier 10 has a generally horizontal upper portion which extends transversely beyond its support 28 and beyond the bracket 22. The length of the carrier is at least equal to the maximum length of the layer of fibers required for the making of a brush. In order to insure that fibers deposited on the carrier will lie transversely thereof, the carrier is provided at its top with a plurality of upward extending transverse teeth 30, these teeth being closely spaced throughout the entire length of the carrier. In order that the carrier 10 may more readily hold the wires A and C deposited thereon by the wire feeding means 16, it is provided with grooves at its ends as indicated at 31 in Figs. 8 and 14.

In order that fibers deposited on the brush may be firmly held in place during movement of the carrier, the carrier is preferably hollow and the interior thereof is connected with a vertical hole 32 extending through the slide extension 28. By means of a flexible hose 34 the hole 32 in the support is connected with a suitable suction device so that a partial vacuum is maintained within the interior of the carrier.

A suitable means is provided for reciprocating the slide 20 between the positions shown in Figs. 8 and 11. These positions are also shown in Figs. 1, 3, 5 and 6. The said means may be widely varied, but as shown, there is a pneumatic cylinder 36 secured to the base 12, this cylinder having a piston therein carried by a piston rod 38 which extends forward and is connected with a depending bracket 40 extending downward from the slide 20. By means of piping 42 and 44 air can be admitted to the cylinder 36 in front of or behind the piston therein so as to move the slide 20 toward the rear or toward the front, as may be required. Air under pressure is supplied through a pipe 46 to a valve unit 48 which is connected with the piping 42 and 44. The valve unit may be operated by any suitable means but as shown there is a handle 50 for this purpose. By manipulating the handle 50 the operator can cause the slide 20, together with the parts carried thereby, to be moved to the rearward position or to the forward position as required.

As already stated, the fiber magazine 14 is preferably located in a relatively elevated position, and when the magazine is so located it is necessary for the carrier 10 to move not only horizontally but also vertically. In order to effect vertical movement of the carrier the supporting slide 24 is provided near its bottom with a transverse extension 52 (Fig. 7), and this extension carries a roller 54 which extends into a cam groove 56 in a bracket 58 secured to the base of the machine. The shape of the cam groove 56 is such that as the slide 20 moves rearward, the slide 24 thereon is moved upward, the amount of upward movement being so determined as to bring the carrier 10 into proper cooperative relationship with the fiber magazine 14 when the slide 20 is in its rear position. When the slide 20 moves forward the cam groove 56 causes the carrier 10 to move downward so that when the slide reaches its forward position the carrier is in register with the twisting position of the twisting mechanism.

As already stated, it is necessary for the carrier 10 to be moved downward after the wires A and C have been engaged by the twisting mechanism preparatory to twisting. The forward end of the cam groove 56 is provided with a downward extension 60 (Figs. 8 and 11) which permits the roller 54 to move downward. When the slide 20 reaches its forward position, the slide 24 which supports the carrier 10 is normally supported by a vertically movable plunger 62 mounted in a bracket 64 on the bracket 58. The plunger 62 is resiliently held in its uppermost position by means of a coil spring 66. The plunger 62 engages the bottom of the extension 52 to thus support the slide 24 and the parts carried thereby. For moving the slide 24 and the parts carried thereby downward, the bracket 58 carries a vertically slideable rod 68 which is engageable at its lower end with the top of the extension 52. The upper end of the rod 68 is pivotally connected with a lever 70 which is pivotally connected with the bed of the machine at 72. The operator, by manually engaging the lever 70, can move the rod 68 downward to thus move the carrier 10 downward in opposition to the spring 66. The carrier is thus separated from the wires and the fibers as shown in Fig. 7 to permit twisting. By moving the lever 70 upward the carrier can be restored to its normal forward position, upward movement being effected by the spring 66. A spring detent 74 on the lever 70

is engageable with depressions in a plate 76, and the lever 70 and the parts controlled thereby can thus be retained in their lower positions or in their upper positions as required.

5 *Twisting mechanism*

The twisting mechanism does not of itself constitute any part of the present invention and it may be of any usual or preferred form and it may in fact be similar to the twisting mechanism shown and described in the before-mentioned Patent No. 2,358,443.

The twisting mechanism comprises the before-mentioned part 18 which is a nonrotatable vise and which includes jaws for gripping the wires A and C at one end. The twisting mechanism also comprises a spindle 77 carrying a rotatable chuck 78 which includes jaws for gripping the wires A and C at the other end.

10 20 The chuck 78 can be rotated by means of belts 79 engaging a pulley 80, the said belts passing over a drive pulley on an electric motor at the rear which is not shown but which is mounted on the slide 20 and bodily movable therewith. The pulley 80 is rotated continuously and rotation can be transmitted to the chuck 78 when required by means of a friction clutch at 81. A hand wheel 82 is provided by means of which the chuck can be rotated manually to a limited extent for a purpose to be explained.

15 25 During twisting the twisting mechanism occupies a position at the front of the machine but it is not necessarily permanently located in this machine. In fact, the twisting mechanism is shown as carried in its entirety on the slide 20 which also supports the carrier 10 and the parts directly associated therewith. Thus the carrier and the twisting mechanism move rearwardly and forwardly in unison and are maintained in fixed relationship with each other, except for the relative vertical movements of the carrier which have been described. When the twisting mechanism is mounted on the slide 20 the driving motor for the chuck 78 is also 30 35 mounted on the slide and moves with it.

40 45 The mechanism for controlling the jaws of the vise 18 and of the chuck 78 need not be described in detail and it is sufficient for purposes of the present invention to state that the said jaws of the vise 18 are operated by a hand lever 83 and that the jaws of the chuck 78 are operated by a hand lever 84. The friction clutch for starting the rotation of the chuck 78 is operated by means of a foot treadle 85 at the front 50 55 of the machine where it can be readily reached by the foot of the operator. By pressing on the foot treadle the friction clutch 81 can be engaged to start rotation of the chuck 78 and effect twisting. Either the vise 18 or the chuck 78 or 60 65 both of them are longitudinally movable on the slide 20 to take care of the shortening of the brush as twisting takes place. Suitable means which need not be described in detail are provided for automatically disengaging the friction clutch after a predetermined amount of shortening of the brush, such shortening being dependent on the amount of twisting.

70 75 When the twisting mechanism is bodily movable with the carrier, it is necessary to provide a suitable connection between the foot treadle and the slide to permit such movement. As shown in Figs. 1 and 8, the foot treadle 85 operates a lever 86 secured to a transverse rock-shaft 87. Mounted on the rockshaft is a lever 78 88 which is splined to the shaft for rotation

therewith but which is movable longitudinally thereof. The lever 88 is held between two brackets depending from the slide 20 so as to be bodily movable with the slide. A member 89 is engaged by the lever 88 and this member serves to operate the clutch 81 by suitable mechanism including a link 90. Thus the clutch is operable by the foot treadle notwithstanding its bodily movements with the slide 20.

In order that the wires A and C may enter the vise 18 and the chuck 78 when the positions shown in Figs. 2 and 4 are reached, the said vise and chuck are provided with vertical wire receiving slots, as shown in Fig. 14. If the slot in the chuck 78 is not initially in its vertical position, the operator can rotate the chuck by means of the hand wheel 82 so that the slot will be in such vertical position, this being done just before the rearward movement of the slide 20 is started. To facilitate entry of the wires into the slots, the vise 18 is provided with upward projecting guides 91, 91 at opposite sides of the slot therein, and similar guides 92, 92 may be formed on the chuck 78 at opposite sides of the slot therein.

Fiber magazine and operating mechanism therefor

The fiber magazine and the operating mechanism therefor do not of themselves constitute any part of the present invention and they may be similar to the magazine and operating mechanism shown in the before-mentioned Patent No. 2,358,443. In describing the fiber magazine and the operating mechanism therefor reference will be had more particularly to Figs. 7, 8, 11, 12, 13, 18, 19 and 20.

The fiber magazine 14 is carried by an elevated platform 94 supported on the base of the machine by means of brackets 96 and 98. The magazine 14 is essentially a rectangular container open at the top and at the bottom, and fibers are placed therein by the operator from time to time so that a sufficient supply is always maintained. One wall of the magazine, as for instance the left wall, may be movable to adjust the length of the magazine for brushes of different lengths. Movable across the bottom of the magazine 14 are two similarly formed, but oppositely positioned, slicing bars 100 and 102. These bars are pointed at their ends, as shown in Fig. 18, and they are connected together for reciprocable movement in unison. Fig. 18 shows the carrier 10 in position immediately below the magazine 14 for receiving a layer of fibers therefrom. The bars 100 and 102 are shown as moving from left to right, and it will be seen that the fibers between the ends of the bars are free to move downwardly onto the carrier. As the bar 102 is withdrawn it permits the fibers to move downwardly, and as the bar 100 advances it slices off a layer of fibers, which layer remains on the carrier 10. The bars support the fibers which are immediately above them, and when the slicing bar 100 has moved entirely across the magazine, it supports all of the fibers, a layer of the said fibers having been sliced off and distributed onto the carrier 10. The length of the layer of the fibers deposited on the carrier 10 is the same as the adjusted length of the magazine.

Suitable mechanism is provided for operating the bars 100 and 102 as soon as the carrier 10 reaches its fiber receiving position, the bars being moved alternately in opposite directions. Fig. 18 shows the bars moving from left to right, and

when the carrier 10 next reaches its fiber receiving position the bars will be moved from right to left, slicing then being effected in the manner already described by the bar 102 instead of by the bar 100.

The two slicing bars 100 and 102 are carried by a slide 104 which is movable horizontally in a guide rail 106 supported by brackets 108, 108 depending from the platform 94. For supporting the slicing bars to prevent vertical vibration thereof two shelves 109, 109 are provided at opposite sides of the magazine 14. The said shelves are carried by the guide rail 106 and they are immediately beneath the bars. The slide 104 is provided with rack teeth on its lower face which mesh with a gear 110, the guide rail 106 being cut away as shown in Fig. 20 to permit the gear to engage the rack teeth. The gear 110 is carried by a shaft 112 rotatable in bearings formed in brackets 114 and 116 depending from the platform 94. Rotatably mounted on the shaft 112 are two bevel gears 118 and 120, these bevel gears meshing with a single bevel gear 122. The bevel gear 122 is mounted on a shaft 124 supported in bearings in brackets 126 and 128 depending from the platform 94. It will be seen that when the shaft 124 and the gear 122 are rotated the bevel gears 118 and 120 are rotated in opposite directions, which directions are indicated by arrows in Fig. 19. Connected with the respective bevel gears 118 and 120 are clutch members 130 and 132 which are adapted to be engaged by a single clutch member 134 rotatable with the shaft 112 but longitudinally movable thereon. By means of a yoke 136 and a lever 138 the clutch member 134 may be moved in one direction or the other to engage either the clutch member 130 or the clutch member 132. Thus the shaft 112 and the gear 110 can be rotated in one direction or the other to move the slide 104 and the slicing bars 100 and 102 in one direction or the other.

Mounted on the guide rail 106 for longitudinal movement is a rod 140, and this rod has a bushing 142 secured thereto, the said bushing being pivotally connected with the lever 138. Secured to the rod 140 are lugs 144 and 146 which project forwardly and are adapted to be engaged by stops 148 and 150 carried by the slide 104. The stops 148 and 150 are so positioned as to engage the respective lugs 144 and 146 at the proper times in order to throw the clutch member 134 from one operative position to the other after the slide 104 and the slicing bars 100 and 102 have been moved sufficiently in one direction or the other. As shown in Figs. 19 and 20, the slide 104 and also the slicing bars and the stop 150 have been moved toward the left so that the stop is in engagement with the lug 146, and the stop has moved the said lug and the rod 140 sufficiently to throw the clutch member 134 out of engagement with the clutch member 132 and into engagement with the clutch member 130. During the next following cycle, the slide 104 and the slicing bars will be moved toward the right until the stop 148 engages the lug 144, thus moving the rod 140 to throw the clutch member 134 out of engagement with the clutch member 130 and into engagement with the clutch member 132. Suitable means, such as an over-center spring 152, is provided to insure movement of the clutch member 134 sufficiently to fully engage the respective clutch members 130 and 132.

Mounted on the shaft 124 is a drive pulley 154 which is rotated by a belt 156 passing over a pulley 158, projecting from a reduction gear unit

160 connected with a motor 162. Connected with the pulley 154 is a clutch 164 which, when engaged, causes the shaft 124 to rotate through a single revolution in the direction indicated in Fig. 19. The clutch 164 has a notch providing an abutment adapted to be engaged by a pawl 166 (Figs. 12 and 13), and this pawl, when engaged, prevents rotation of the shaft. The pawl 166 is mounted on a shaft 168 (Figs. 12, 13 and 19) and a spring 170 biases the pawl toward its engaging position. At the right end of the shaft 168 is a toothed member 172 which has a lost motion relationship with the shaft, being normally held by a spring 173 in the relative position shown in Fig. 12. Positioned below and parallel with the shaft 168 is a rockshaft 174 carrying at its right end a toothed member 176 adapted to engage the toothed member 172. At the left end of the shaft 174 is a lever 178 (Figs. 13 and 20) carrying a projecting pin 180. A spring 182 biases the shaft 174 so that the pin 180 is normally held in its forward position, as limited by a stop pin 184. With the parts in the positions described the tooth on the member 176 is in front of the tooth on the member 172 as shown in Figs. 8, 11 and 12.

Carried by the bracket 22 on the slide 20 is a member 186 which is so positioned that it engages the pin 180 as the slide 20 reaches its rearward position with the carrier 10 immediately below the magazine 14. The pin 180 is moved rearward thus turning the rockshaft 174 in the counterclockwise direction as viewed in Fig. 13, or in the clockwise direction as viewed in Fig. 12. The rockshaft 174, moving in the clockwise direction as viewed in Fig. 12, moves the toothed member 176 in the same direction, thus causing the tooth thereon to engage the tooth on the toothed member 172 and moving the rockshaft 168 and the pawl 166 in the counterclockwise direction to disengage the pawl from the one-revolution clutch 164. This starts the rotation of the shaft 124 in the clockwise direction thus moving the slicing bars 100 and 102 in one direction or the other by means of the mechanism which has already been described.

As soon as the teeth on the members 176 and 172 have become disengaged, the pawl is free to move rearwardly under the influence of the spring 170, and is ready to engage the notch in the clutch at the completion of a single revolution, thus stopping further rotation of the shaft 124 and of the parts connected therewith. After the fibers have been distributed on the carrier 10 by means of one or the other of the slicing bars, the slide 20 and the parts carried thereby, including the member 186, are moved in the forward direction, and the rockshaft 174 is moved by the spring 182 so that the said shaft and the parts carried thereby, including the toothed member 176, are restored to the positions shown in Figs. 12 and 13. The tooth on the member 176, in moving forward, must pass by the tooth on the member 172. This is made possible by the before-mentioned lost motion connection of the member 172 with the shaft 168. The member 172 is rotated in the clockwise direction, as viewed in Fig. 12, in opposition to the spring 173 sufficiently to permit the tooth on the member 176 to pass. Then the member 172 is restored by the spring to the position shown in Fig. 12.

Wire feeding means

In describing the wire feeding means reference

will be had more particularly to Figs. 7, 8, 9, 10, 15, 16 and 17.

Depending from the platform 94 are two brackets 188 and 190, and these brackets carry a horizontal plate 192. Supported on the plate 192 are two pairs of blocks 194 and 196. The two pairs of blocks are spaced apart longitudinally as shown in Figs. 7 and 15. Carried by the front blocks 194, 194 is an inclined plate 198 which serves as one wall of a wire magazine 200. The blocks of each pair are spaced apart as shown in Fig. 17 to provide a vertical wire channel 202 communicating with the magazine 200. Mounted in apertures in the blocks 196, 196 is a rotatable shaft 204 which carries a longitudinal serrated roller 206, the length of which is only a little less than the total distance between the blocks. At the left end of the shaft 204 is a manually operable knob 208.

Carried by studs projecting toward the right from the right hand blocks 194, 196 is a vertical plate 210, the upper end of which is flared toward the right. Carried by studs projecting toward the left from the left hand blocks 194, 196 is a vertical plate 212, the upper end of which is flared toward the left. The spacing between the plates 210 and 212 is substantially equal to the length of the wires that are to be used, and these plates serve to hold the wires in proper positions and to prevent them from being displaced longitudinally. If the length of the wires is to be changed the plate 212 can be moved toward the right or toward the left by replacing the studs which carry it and by substituting longer or shorter studs.

In use a supply of wires cut to suitable length is placed in the magazine 200, the wires being located as to their longitudinal positions by the plates 210 and 212. The wires tend to move by gravity into the channel 202 which is ordinarily completely filled. The roller 206 serves as an agitator for the wires and if the wires fail to move freely by gravity into the channel 202, the roller can be turned by means of the knob 208 to agitate the wires and facilitate their entry into the channel 202.

Mounted in bearing brackets 214 and 216 below the plate 192 is a rockshaft 218. Secured to the rockshaft are two segments 220 and 222 which are immediately beneath the lower end of the wire channel 202, each segment having a wire receiving notch 224 therein, as shown in Fig. 17. When the segments are in their normal positions, as shown in Fig. 8, the notch 224 of each segment is immediately beneath the wire channel 202 so as to receive one wire therefrom. When the segments are rotated through approximately 90° in the counterclockwise direction to the position shown in Fig. 17, the wire 60 entered in the two notches is moved to the position shown in Fig. 17, and the wire can then drop onto the carrier 10 when the said carrier is either in the position shown in Fig. 2 or the position shown in Fig. 4. The shaft 218 is normally positioned to hold the notches 224 in register with the wire channel 202 by means of a spring 226 which engages a pin on an arm 228 secured to the shaft.

Secured to the shaft 218 at the right end thereof is a cam member 230. This cam member has a tooth 232 which extends in a generally downward direction when the cam member is in its normal position as shown in Fig. 8. The cam member also carries a pin 234 which projects 75 toward the right.

Suitably secured in fixed position on the slide 20 is a cam member 236, this cam member being so positioned that it can engage the pin 234 when the slide is moved. Pivotaly mounted on the cam member 236 is a second cam member 238 which is positioned to engage with the tooth 232 of the cam member 230 when the slide is moved. The cam member 238 is biased by a spring 240 and is normally held in the relative position shown in Fig. 9.

When the slide 20 and the parts carried thereby move rearward the cam member 238 engages the tooth 232 and moves the said tooth from the position shown in Fig. 8 to the position shown in Fig. 9. Thus the shaft 218 and the parts carried thereby are rocked in the counterclockwise direction from the positions shown in Fig. 8 to the positions shown in Figs. 9, 16 and 17, and a single wire is released from the notches 224 in the segments 220, 222. This wire falls onto the carrier 10 which is then in the position shown in Fig. 2. As soon as the cam member 238 passes beyond the position shown in Fig. 9, the shaft 218 and the parts carried thereby are restored to their normal positions by the spring 240. It will be seen, by reference to Fig. 9, that the pin 234 has been moved to a position such that it is not engaged by the cam member 236 as the said cam member moves rearward.

When the slide 20 and the parts carried thereby are returned in the forward direction, the cam member 236 engages the pin 234 to again rock the shaft 218 and the parts carried thereby in the counterclockwise direction from the positions shown in Fig. 8 to the positions shown in Figs. 10, 16 and 19. Again a single wire is released from the notches 224 in the segments 220, 222. This wire falls onto the carrier 10 which is then in the position shown in Fig. 4. As the parts move in the forward direction the cam member 238 may reengage the tooth 232 as shown in Fig. 10. Such engagement causes the cam member 238 to turn in the clockwise direction in opposition to the spring 240, and it is thus able to pass by the tooth 232. After passing the said tooth 232 the cam member 238 is returned to its normal position by the spring 240.

Operation

During operation of the machine the operator maintains a supply of fibers in the fiber magazine 14, placing additional fibers therein as the supply is depleted. The operator also maintains a supply of wires in the wire magazine 200, rotating the agitating roller 206 from time to time as may be necessary to keep the wire channel 202 filled.

With the slide 20 in its forward position the operator turns the chuck 78 by means of the hand wheel 82 to whatever extent may be necessary to bring the slot therein in vertical position as shown in Fig. 14. Then the operator, by means of the handle 50 and the valve unit 48, causes the slide and the various parts carried thereby to move to the rearward position and then back to the forward position. As the slide moves rearwardly one wire from the wire feeding means 16 is deposited on the carrier in the manner already described, the ends of this wire passing into the vertical slots in the vise 18 and in the chuck 78. When the slide reaches its rearward position the carrier 10 has been moved upward so that it is immediately beneath the magazine 14 as shown in Fig. 18, and the member 186 engages the pin 180 to release the one-revolution 75

clutch 164 thus starting the movement of the slicing bars 100 and 102. If the slicing bars are in their left hand positions, as shown in Figs. 1, 19 and 20, the gear wheel 110 is rotated in the clockwise direction to move the bars from left to right, thus slicing off a layer of fibers from the supply in the magazine 14, as clearly illustrated in Fig. 18. Inasmuch as one wire has been previously deposited on the carrier 10 the layer 10 of fibers is above the said wire. When the slicing bars have completed their movement, the stop 148 engages the lug 144 to throw the clutch member 134 from the position shown in Fig. 19 to its opposite position. At or about the time the 15 clutch is shifted, the shaft 124 has completed its single revolution and the slicing bars remain in their right hand positions ready for the next cycle.

As the slide 20 and the parts carried thereby 20 move forwardly a second wire is deposited from the wire feeding means 16 onto the carrier, this second wire falling on top of the fibers which are thus positioned between the two wires. The ends 25 of the second wire also enter the vertical slots in the vise 18 and in the chuck 78.

After the slide and the parts carried thereby have reached the forward position, the operator can then inspect the fibers to make sure that they are uniformly distributed and otherwise in proper condition for twisting. For some brushes it is found desirable to remove a few fibers from each end of the layer to insure more satisfactory twisting. After the operator has inspected the fibers and has made any necessary changes in the 30 distribution thereof, the jaws of the vise 18 and of the chuck 78 can be engaged with the wires by means of the levers 83 and 84. By means of the lever 70 the carrier 10 is lowered by the operator to the position shown in Fig. 7 so that the carrier 35 will not interfere in any way with the twisting operation. The next step is for the operator to start the twisting by depressing the foot treadle 85 so as to engage the clutch 81. After the brush has been fully twisted, as shown in Fig. 7, the 40 twisting is stopped and the jaws of the vise and the chuck may be temporarily disengaged from the wires and the vise and chuck may be separated and again reengaged with the wires. After 45 that a supplemental twisting of the ends of the wires may be effected to twist the end portions thereof in such a manner that they are in condition to be subsequently engaged by the handle in which the brush is to be mounted.

After the twisting of the brush has been completed and the twisted brush has been removed, the carrier 10 is moved upward by the lever 70 and the machine is ready for the making of the next following brush. In making such next following brush the procedure is exactly the same as that already described except that the slicing bars move from right to left instead of from 50 left to right.

What I claim is:

1. The combination in a brush making machine, of a magazine for brush fibers, a twisting mechanism having an operative position horizontally spaced from the fiber magazine and parallel therewith, a carrier for wires and fibers, means for moving the carrier to a position beneath and close to the fiber magazine and for then moving it translationally and in parallelism to a position in alignment with the operative position of the twisting mechanism, and means for separating fibers from the fiber magazine and dis-

tributing them on the carrier while in its position beneath the said magazine.

2. The combination in a brush making machine, of a magazine for brush fibers, a twisting mechanism having an operative position horizontally spaced from the fiber magazine and parallel therewith, a carrier for wires and fibers, means for moving the carrier to a position beneath and close to the fiber magazine and for then moving it translationally and in parallelism to a position in alignment with the operative position of the twisting mechanism, means for separating fibers from the fiber magazine and distributing them on the carrier while in its position beneath the said magazine, and wire feeding means for feeding a wire to the carrier prior to the distribution of the fibers thereon and for feeding a second wire to the carrier after the distribution of the fibers thereon.

3. The combination in a brush making machine, of a magazine for brush fibers, a twisting mechanism having an operative position horizontally spaced forwardly from the fiber magazine, a carrier for wires and fibers, means for moving the carrier in a cycle rearwardly from a position in alignment with the operative position of the twisting mechanism to a position beneath and close to the fiber magazine and then forwardly to its first said position, means for separating fibers from the fiber magazine and distributing them on the carrier while in its second said position, and automatic means dependent on the movement of the carrier to its rearward position for operating the fiber separating and distributing means.

4. The combination in a brush making machine, of a magazine for brush fibers, a twisting mechanism having an operative position horizontally spaced forwardly from the fiber magazine, a carrier for wires and fibers, means for moving the carrier in a cycle rearwardly from a position in alignment with the operative position of the twisting mechanism to a position beneath and close to the fiber magazine and then forwardly to its first said position, means for separating fibers from the fiber magazine and distributing them on the carrier while in its second said position, and automatic wire feeding means operative in timed relationship with each cycle of movement of the carrier for feeding a wire thereto prior to the distribution of the fibers thereon and for feeding a second wire thereto after the distribution of the fibers thereon.

5. The combination in a brush making machine, of a magazine for brush fibers, a twisting mechanism having an operative position horizontally spaced forwardly from the fiber magazine, a carrier for wires and fibers, means for moving the carrier in a cycle rearwardly from a position in alignment with the operative position of the twisting mechanism to a position beneath and close to the fiber magazine and then forwardly to its first said position, means for separating fibers from the fiber magazine and distributing them on the carrier while in its second said position, and automatic wire feeding means operative during each cycle of movement of the carrier for feeding a wire thereto during its rearward movement from the first said position to the second position and for feeding a second wire thereto during its forward movement from the second said position to the first said position.

6. In a brush making machine, the combination of a magazine for brush fibers, a twisting mechanism having an operative position hori-

zontally spaced forwardly from the fiber magazine and also spaced downwardly therefrom, a carrier for wires and fibers, means for moving the carrier in a cycle from a forward lower position in alignment with the operative position of the twisting mechanism to a rearward upper position beneath and close to the fiber magazine and then from its said rearward upper position to its said forward lower position, and means for separating fibers from the fiber magazine and distributing them on the carrier while in its rearward upper position.

7. In a brush making machine, the combination of a magazine for brush fibers, a twisting mechanism having an operative position horizontally spaced forwardly from the fiber magazine and also spaced downwardly therefrom, a carrier for wires and fibers, means for moving the carrier in a cycle from a forward lower position in alignment with the operative position of the twisting mechanism to a rearward upper position beneath and close to the fiber magazine and then from its said rearward upper position to its said forward lower position, means for separating fibers from the fiber magazine and distributing them on the carrier while in its rearward upper position, and wire feeding means for feeding a wire to the carrier prior to the distribution of the fibers thereof and for feeding a second wire to the carrier after the distribution of the fibers thereon.

8. In a brush making machine, the combination of a magazine for brush fibers, a twisting mechanism having an operative position horizontally spaced forwardly from the fiber magazine and also spaced downwardly therefrom, a carrier for wires and fibers, means for moving the carrier in a cycle from a forward lower position in alignment with the operative position of the twisting mechanism to a rearward upper position beneath and close to the fiber magazine and then from its said rearward upper position to its said forward lower position, means for separating fibers from the fiber magazine and distributing them on the carrier while in its rearward upper position, and automatic wire feeding means operative during each cycle of movement of the carrier for feeding a wire thereto during its rearward movement from the first said position to the second position and for feeding a second wire thereto during its forward movement from the second said position to the first said position.

9. A brush making machine comprising in combination, a magazine for brush fibers, a twisting mechanism having an operative position horizontally spaced from the fiber magazine and parallel therewith, a carrier for wires and fibers, means for moving the carrier to a position beneath and close to the fiber magazine and for then moving it translationally and in parallelism to a position in alignment with the operative position of the twisting mechanism, means for separating fibers from the fiber magazine and distributing them on the carrier while in its position beneath the said magazine, and means for moving the carrier downward from its position in alignment with the operative position of the twisting mechanism to permit the assembly of wires and fibers to be twisted by the said twisting mechanism.

10. A brush making machine comprising in combination, a magazine for brush fibers, a twisting mechanism having an operative position horizontally spaced forwardly from the fiber

magazine, a carrier for wires and fibers, means for moving the carrier in a cycle rearwardly from a position in alignment with the operative position of the twisting mechanism to a position beneath and close to the fiber magazine and then forwardly to its first said position, means for separating fibers from the fiber magazine and distributing them on the carrier while in its second said position, and means for moving the carrier downward from its position in alignment with the operative position of the twisting mechanism to permit the assembly of wires and fibers to be twisted by the said twisting mechanism.

11. A brush making machine comprising in combination, a magazine for brush fibers, a twisting mechanism having an operative position horizontally spaced forwardly from the fiber magazine, a carrier for wires and fibers, means for moving the carrier in a cycle rearwardly from a position in alignment with the operative position of the twisting mechanism to a position beneath and close to the fiber magazine and then forwardly to its first said position, means for separating fibers from the fiber magazine and distributing them on the carrier while in its second said position, automatic wire feeding means operative during each cycle of movement of the carrier for feeding a wire thereto during its movement from the first position to the second position and for feeding a second wire thereto during its movement from the second position to the first position, and means for moving the carrier downwardly from its position in alignment with the operative position of the twisting mechanism to permit the assembly of wires and fibers to be twisted by the said twisting mechanism.

12. A brush making machine comprising in combination, a magazine for brush fibers, a twisting mechanism having an operative position horizontally spaced forwardly from the fiber magazine and also spaced downwardly therefrom, a carrier for wires and fibers, means for moving the carrier in a cycle from a forward lower position in alignment with the operative position of the twisting mechanism to a rearward upper position beneath and close to the fiber magazine and then from its said rearward upper position to its said forward lower position, means for separating fibers from the fiber magazine and distributing them on the carrier while in its rearward upper position, and means for moving the carrier downwardly from its said forward lower position to permit the assembly of wires and fibers to be twisted by the said twisting mechanism.

13. A brush making machine comprising in combination, a magazine for brush fibers, a twisting mechanism having an operative position horizontally spaced forwardly from the fiber magazine and also spaced downwardly therefrom, a carrier for wires and fibers, means for moving the carrier in a cycle from a forward lower position in alignment with the operative position of the twisting mechanism to a rearward upper position beneath and close to the fiber magazine and then from its said rearward upper position to its said forward lower position, means for separating fibers from the fiber magazine and distributing them on the carrier while in its rearward upper position, automatic wire feeding means operative during each cycle of movement of the carrier for feeding a wire thereto during its rearward movement from the first said position to the second position and for feeding a second wire thereto during its forward movement

from the second said position to the first said position, and means for moving the carrier downwardly from its said forward lower position to permit the assembly of wires and fibers to be twisted by the said twisting mechanism to operate.

14. The combination in a brush making machine, of a magazine for brush fibers, a twisting mechanism having an operative position horizontally spaced forwardly from the fiber magazine and also spaced downwardly therefrom, a horizontally movable slide, a carrier for wires and fibers movable with the slide and also vertically movable with respect thereto, means for moving the slide rearwardly and then forwardly and for moving the carrier upwardly as the slide moves rearwardly and then downwardly as the slide moves forwardly whereby the carrier is moved in a cycle rearwardly and upwardly from a forward lower position in alignment with the operative position of the twisting mechanism to a rearward upper position beneath and close to the fiber magazine and then forwardly and downwardly to its said forward lower position, and means for separating fibers from the fiber magazine and distributing them on the carrier while in its rearward upper position.

15. The combination in a brush making machine, of a magazine for brush fibers, a twisting mechanism having an operative position horizontally spaced forwardly from the fiber magazine and also spaced downwardly therefrom, a horizontally movable slide, a carrier for wires and fibers movable with the slide and also vertically movable with respect thereto, means for moving the slide rearwardly and then forwardly, a stationary cam for moving the carrier upwardly as the slide moves rearwardly and then downwardly as the slide moves forwardly whereby the carrier is moved in a cycle rearwardly and upwardly from a forward lower position in alignment with the operative position of the twisting mechanism to a rearward upper position beneath and close to the fiber magazine and then forwardly and downwardly to its said forward lower position, and means for separating fibers from the fiber magazine and distributing them on the carrier while in its rearward upper position.

16. The combination in a brush making machine, of a magazine for brush fibers, a twisting mechanism having an operative position horizontally spaced forwardly from the fiber magazine and also spaced downwardly therefrom, a horizontally movable slide, a carrier for wires and fibers movable with the slide and also vertically movable with respect thereto, means for moving the slide rearwardly and then forwardly and for moving the carrier upwardly as the slide moves rearwardly and then downwardly as the slide moves forwardly whereby the carrier is moved in a cycle rearwardly and upwardly from a forward lower position in alignment with the operative position of the twisting mechanism to a rearward upper position beneath and close to the fiber magazine and then forwardly and downwardly to its said forward lower position, means for separating fibers from the fiber magazine and distributing them on the carrier while in its rearward upper position, and means for moving the carrier downwardly with respect to the slide from its said forward lower position to permit the assembly of wires and slides to be twisted by the said twisting mechanism.

17. The combination in a brush making machine, of a magazine for brush fibers, a twisting

mechanism having an operative position horizontally spaced forwardly from the fiber magazine and also spaced downwardly therefrom, a horizontally movable slide, a carrier for wires and fibers movable with the slide and also vertically movable with respect thereto, means for moving the slide rearwardly and then forwardly, a cam follower connected with the carrier, a stationary member having a cam groove therein for receiving the cam follower, the said cam groove having a downward opening at its forward end and the said cam groove being inclined to move the carrier upwardly as the slide moves rearwardly and then downwardly as the slide moves forwardly whereby the carrier is moved in a cycle rearwardly and upwardly from a forward lower position in alignment with the operative position of the twisting mechanism to a rearward upper position beneath and close to the fiber magazine and then forwardly and downwardly to its said forward lower position, means for separating fibers from the fiber magazine and distributing them on the carrier while in its rearward upper position, and means for moving the carrier downwardly with respect to the slide from its said forward lower position with the cam follower moving downward through the downward opening in the cam groove.

18. In a brush making machine, the combination of a magazine for brush fibers, a bodily movable twisting mechanism, a carrier for wires and fibers bodily movable with the twisting mechanism, means for moving the twisting mechanism and the carrier to positions wherein the carrier is beneath and close to the fiber magazine and then to positions wherein the said twisting mechanism and carrier are horizontally spaced from the magazine and wherein the carrier is in alignment with the twisting mechanism, and means for separating fibers from the fiber magazine and distributing them on the carrier while the carrier is in its position beneath the said magazine.

19. In a brush making machine, the combination of a magazine for brush fibers, a bodily movable twisting mechanism, a carrier for wires and fibers bodily movable with the twisting mechanism, means for moving the twisting mechanism and the carrier in a cycle rearwardly from forward twisting positions horizontally spaced from the magazine to positions wherein the carrier is beneath and close to the fiber magazine and then forwardly to the said forward twisting positions, and means for separating fibers from the fiber magazine and distributing them on the carrier while the carrier is in its position beneath the said magazine.

20. In a brush making machine, the combination of a magazine for brush fibers, a bodily movable twisting mechanism, a carrier for wires and fibers bodily movable with the twisting mechanism, means for moving the twisting mechanism and the carrier in a cycle rearwardly from forward twisting positions horizontally spaced from the magazine to positions wherein the carrier is beneath and close to the fiber magazine and then forwardly to the said forward twisting positions, means for separating fibers from the fiber magazine and distributing them on the carrier while the carrier is in its position beneath the said magazine, and automatic wire feeding means operative in timed relationship with each cycle of movement of the carrier for feeding a wire thereto prior to the distribution of the fibers thereon and for feeding a second wire thereto after the distribution of the fibers thereon,

21. A brush making machine comprising in combination, a magazine for brush fibers, a twisting mechanism having an operative position horizontally spaced forwardly from the fiber magazine and also spaced downwardly therefrom, a horizontally movable slide supporting the twisting mechanism, a carrier for wires and fibers movable with the slide and also vertically movable with respect thereto, means for moving the slide rearwardly and then forwardly and for moving the carrier upwardly as the slide moves rearwardly and then downwardly as the slide moves forwardly whereby the carrier is moved in a cycle rearwardly and upwardly from a forward lower position in alignment with the operative position of the twisting mechanism to a rearward upper position beneath and close to the fiber magazine and then forwardly and downwardly to its said forward lower position, and means for separating fibers from the fiber magazine and distributing them on the carrier while in its rearward upper position.

22. A brush making machine comprising in combination, a magazine for brush fibers, a twisting mechanism having an operative position horizontally spaced forwardly from the fiber magazine and also spaced downwardly therefrom, a horizontally movable slide supporting the twisting mechanism, a carrier for wires and fibers movable with the slide and also vertically movable with respect thereto, means for moving the slide rearwardly and then forwardly and for moving the carrier upwardly as the slide moves rearwardly and then downwardly as the slide moves forwardly whereby the carrier is moved in a cycle rearwardly and upwardly from a forward lower position in alignment with the operative position of the twisting mechanism to a rearward upper position beneath and close to the fiber magazine and then forwardly and downwardly to its said forward lower position, means for separating fibers from the fiber magazine and distributing them on the carrier while in its rearward upper position, and automatic wire feeding means operative in timed relationship with each cycle of movement of the carrier for feeding a wire thereto prior to the distribution of the fibers thereon and for feeding a second wire thereto after the distribution of the fibers thereon.

23. A brush making machine comprising in combination, a magazine for brush fibers, a twisting mechanism having an operative position horizontally spaced forwardly from the fiber magazine and also spaced downwardly therefrom, a horizontally movable slide supporting the twisting mechanism, a carrier for wires and fibers movable with the slide and also vertically movable with respect thereto, means for moving the slide rearwardly and then forwardly and for moving the carrier upwardly as the slide moves rearwardly and then downwardly as the slide moves forwardly whereby the carrier is moved in a cycle rearwardly and upwardly from a forward lower position in alignment with the operative position of the twisting mechanism to a rearward upper position beneath and close to the fiber magazine and then forwardly and downwardly to its said forward lower position, means for separating fibers from the fiber magazine and distributing them on the carrier while in its rearward upper position, and means for moving the carrier downwardly from its said forward lower position to permit the assembly of wires and fibers to be twisted by the said twisting mechanism.

24. A brush making machine comprising in combination, a magazine for brush fibers, a twisting mechanism having an operative position horizontally spaced forwardly from the fiber magazine and also spaced downwardly therefrom, a horizontally movable slide supporting the twisting mechanism, a carrier for wires and fibers movable with the slide and also vertically movable with respect thereto, means for moving the slide rearwardly and then forwardly and for moving the carrier upwardly as the slide moves rearwardly and then downwardly as the slide moves forwardly whereby the carrier is moved in a cycle rearwardly and upwardly from a forward lower position in alignment with the operative position of the twisting mechanism to a rearward upper position beneath and close to the fiber magazine and then forwardly and downwardly to its said forward lower position, means for separating fibers from the fiber magazine and

distributing them on the carrier while in its rearward upper position, and automatic wire feeding means operative during each cycle of movement of the carrier for feeding a wire thereto during its rearward movement from the first said position to the second position and for feeding a second wire thereto during its forward movement from the second said position to the first said position.
